METHOD OF MAKING SHOE SOLES

Warren Oakley Cagney, Garden City, N. Y., assignor to Cagney-Storer, Inc., New York, N. Y., a corporation of New York

Application December 14, 1942, Serial No. 468,970

1 Claim. (Cl. 12—146)

The present invention relates to a shoe sole and method of making the same.

An object of the invention is to provide a shoe sole formed of wood or similar bodily rigid material, but which will be extremely flexible.

Another object of the invention is to provide a shoe sole which includes no leather.

In the designing of a sole formed of wood and which is nevertheless flexible to accommodate the bending of the foot which occurs during walking, the usual procedure has been to provide a number of wood sections on the sole to enable it to bend at any one of a number of points. However, if a wood sole is to have the bending characteristics of a leather sole, it is also desirable that while it may sharply bend at necessary points, the sections immediately adjacent the sharp bend must assume a position along a gradually curved line. For example, at the moment during walking when the weight of the foot rests upon the toe, a shoe bends sharply just behind the toe, and the portion of the sole immediately behind this sharp bend is bent along a gradually curved line.

It is quite obvious that previously designed wooden soles formed of only several wooden sections cannot simulate the characteristics of a leather sole in the above respect. It is also clear that wooden soles which do not bend on lines extending at right angles to the length of the sole will not have the above desirable characteristic.

Another desideratum of a wooden sole must be to so connect the wooden sections, or so form them with respect to each other, that while adjacent sections may bend with respect to each other, no section may move directly upwardly or translationally or tilt laterally with respect to the immediately adjacent sections. Otherwise, if one section bears upon a small stone or other protuberance, that section alone will press upwardly upon the foot, resulting in discomfort. It will be appreciated that because leather soles are relatively thick, they avoid this objection because the pressure of any protuberance on the ground is at least distributed over a wide area.

One principal objection to forming a wooden sole of a large number of small sections is that while they may bend with respect to each other at any one of numerous points, it is extremely difficult to so support them with respect to each other that one section cannot move upwardly or translationally with respect to immediately adjacent sections.

An important object of the present invention is to provide a sole formed of wood and which includes no leather, but which has the desirable bending but non-translationally movable characteristics of leather.

A further object of the invention is to provide a sole formed of wood sections which are so supported with respect to each other and of such relative design that while free bending on cross-wise lines is permitted, no translational movement or lateral tilting of one section with respect to an immediately adjacent section can occur.

The above mentioned object of providing a sole which will bend is obtained in the present invention by forming the sole of a layer of wood which is so grooved on its undersurface that one section may bend upwardly with respect to adjacent sections and by applying a backing of heavy fabric such as canvas or other bendable or bodily flexible material to the upper surface of the sole. Bending along proper lines is assured by dividing the sections from each other on lines extending at right angles of the length of the sole.

The desirable characteristic of preventing upward translational movement or lateral tilting between immediately adjacent sections of the present sole is obtained partly by the fact that the sections are held closely together by the backing of canvas or other bendable material discussed above. However, by the present invention, upward translational movement and lateral tilting of one section with respect to the next adjacent one is further prevented by reason of the fact that the wooden tread of the sole is so constructed as to avoid such movement. More particularly, by the present invention, the wooden sole is initially in the form of one or more strips of wood divided crosswise by grooves which do not extend entirely to the upper surface of the strip. In other words, an unbroken area is provided between the grooves or cuts in the bottom of the strip and the upper surface of the strip. Before the sole is applied to a shoe, the strip may be broken by bending at several of the dividing grooves between the sections. Furthermore, during walking the wood strip may be broken by the bending of the wearer's foot and to suit the requirements of the foot. In any event, I have found that by careful selection of the type of wood used in the sole, the breaking of the strip will always occur on irregular vertical lines if the wood is of proper characteristics. That is, breaking will not occur on straight lines.

extending normal to the upper surface of the wood strip but always on a jagged or angled line. Because of this, while each section will be free to bend with respect to adjacent sections, upward translational movement of any section relative to the immediately adjacent section will be entirely prevented because of the fact that when two adjacent sections lie in the same plane, they will be interlocked because of the irregular line of breakage. The same action will obviously prevent one section from tilting laterally with respect to an immediately adjacent section.

Another object of the invention is to provide a wooden shoe sole which is so formed on its lower surface that slippage will be prevented and good traction can be obtained under all conditions.

A further object of the invention is to provide a method whereby wooden soles of the desired design may be formed from blanks with a minimum waste of material and at a high rate of production.

I have found that it is undesirable to form a wooden sole from a strip of wood having its grain running lengthwise of the strip if the strip has a width comparable to the length of the sole, because wood of this width with longitudinally extending graining is extremely apt to be warped. The use of warped wood would naturally result in discomfort to the wearer.

By the present invention, the sole is preferably formed of two strips of wood, each of such width as to obviate the possibility of the wood being warped. In manufacture, the two strips are placed side by side with their graining parallel and the forward portion of a sole is cut from one strip while the rear portion is cut from the other strip. By maintaining the two strips in close contact, no gap will be provided in the sole.

In order to assure that the entire wooden sole will be properly supported by the backing material regardless of the fact that the sole is formed from two separate strips of wood, the present method involves cementing both strips of wood to canvas or other backing, and with their edges in close contact, before cutting out the soles. In this way, the complete sole including the wooden tread portion and the backing is provided in one operation and without the necessity of having to carefully fit a backing element to the wood after the cutting operation.

It is desirable that the toe portion of the wood sole have a somewhat different bottom surface configuration from the remaining portions of the sole. This necessitates having one edge of the wood from which a sole is cut provided with a special formation. Ordinarily, if the soles were formed of two strips, as heretofore has been stated to be desirable, it would be necessary to form one of these strips to include a toe portion while the other strip would include no toe portion. In other words, two types of parent strips would have to be provided. By the method included in the present invention, both strips have the same formation, and they are placed together on the backing material with the toe forming portions at the outer edges of the material. Then the cutting is so performed that alternate soles cut from the strip will face in opposite directions. Thus, the toe of the one sole will be formed from the toe portion of one strip while the toe of the next adjacent sole will be formed from the toe portion of the other strip. In addition to avoiding the necessity of

producing two different types of strips, this method of cutting likewise enables a maximum number of soles to be cut from the strips because the wide ball portion of one sole will be cut from a portion of the parent strip alongside the portion of the parent strip from which the relatively narrow heel portion of the next adjacent sole is cut.

5 A further object of the invention is to form 10 a shoe or sandal having a sole formed of wooden material which is so ridged that its instep portion may be curved upwardly to form a rigid arched instep for the shoe or sandal.

15 Other objects and advantages of the invention will be apparent from the attached drawing and following specification.

In the drawing,

Figure 1 is a bottom plan view of a sole of the present invention.

Figure 2 is a side elevation of the sole.

Figure 3 is an enlarged vertical section of a fragment of a sole before breaking between sections.

20 Figure 4 is a view similar to Figure 3, but 25 showing the sections broken with respect to each other.

Figure 5 is a plan view of a portion of a length or strip of wood used in the formation of a sole of the present invention, the view showing the tread surface.

30 Figure 6 is a perspective view of a portion of the strip of Figure 5, but with the top surface of the strip uppermost.

Figure 7 shows two strips such as illustrated 35 in Figure 5 mounted upon a layer of backing material, and the manner of exerting pressure thereon, and

Figure 8 shows the manner of cutting soles from the wood and fabric assembly of Figure 7.

40 The shoe sole of the present invention is formed from strips 10 formed of a wood which is hard, close-grained, and which will break on irregular lines. Birch, maple, poplar, or cherry, are woods having these characteristics. The strips 10 are 45 ordinarily in three foot lengths and have a width of approximately 5 1/2", although the width may vary according to the size of the soles to be formed. The grain runs lengthwise of the strips. Each strip 10 is provided on one sur-

50 face 11 with shallow and closely spaced scorings 12. As is hereinafter explained, the surface 11 forms the upper face of the wooden element of a sole. The opposite surface 13 of the strip 10 is flat and ungrooved over an area 14 55 extending from one edge 15 and which area is approximately 1" to 1 1/2" wide. The remainder of the surface 13 is formed into equidistantly spaced substantially "half round" ridges 16, as best shown in the fragment of a completed sole 60 shown in Figure 3. As an example, each ridge 16 is 5/8" in width between each of its bases 17, and, with this width, would be about 3/16" high in a strip about 1 1/8" in thickness. It will thus be seen that a ridge 16 is not a complete 65 semi-circle, and that an ungrooved thickness of 3/16" exists between the bases 17 of the ridges and the opposite and scored surface 11. As also shown in Figure 3, the bases of the ridges need not join each other, but are preferably separated by flat portions 18 which are usually about 70 1/8" wide.

After a strip 10 has been milled to the form described above, preferably by a planing machine, a waterproof adhesive is applied to the 75 scored surface 11. Two strips 10 are then placed

side by side in the relation illustrated in Figure 8, i. e., with the ungrooved areas 14 outermost, and with the opposite edges 19 of the strips in close contact. The two strips thus assembled are then placed upon a sheet of fabric 20, such as heavy duck, for example, 18 oz. duck. However, press cloth, or filter cloth may be used as a backing element if this element is formed of a fabric. Use of a fabric is not necessary, since any bodily flexible material may be used for this purpose, for example, any resinous or nitrocelulose material which is bodily flexible.

The assembled structure is then placed in a veneer press for approximately 24 hours, in order that the fabric and wood strips will be permanently secured together. It is to be noted that the two strips 10 have their edges 16 in close contact with each other on the layer of fabric, so that no space will be provided between these edges of the strips.

It is highly desirable to form the soles from two strips 10 which are each of a width approximately one-half the length of the sole, instead of from a single strip of a width approximating the length of the sole. This is due to the fact that a strip of wood as thin as that used and having the substantial width required to produce the full length of a sole would be very apt to be warped, which would make the final sole uncomfortable. The use of strips 10 of the width referred to above obviates warped material.

After the assembly shown in Figures 7 and 8 is removed from the veneer press, the soles of the present invention are cut from it by means of a band-saw. Figure 8 shows the method of cutting the strips, and it will be observed from this that alternate soles cut from the strip extend in opposite directions. More particularly, the toe portion 21 of one sole 22 is cut from the ungrooved portion 14 of the left-hand strip 10, while the toe portion of the next adjacent sole 22 is cut from the ungrooved portion 14 of the other strip 10. In this way, a maximum number of soles can be cut from a blank formed of two strips 10. In addition, by having the soles extend oppositely, the strips 10 can be of identical form, that is, both strips may be formed with ungrooved portions 14, instead of having one strip formed with an ungrooved portion 14, and the other strip provided over its entire surface 13 with half round ridges.

After the soles 22 have been cut out as just described, the upper surface of the fabric is buffed to provide a good bonding surface for joining to a shoe or sandal. The upper surface of the fabric may be cemented to an insole or to a platform. In each case buffing is essential.

Staples 24 of U-shaped form are driven into some of the ridge portions of the sole 22, with the points of the staples entering the fabric 20. Thus, the heads of the staples will be embedded in the fabric, and no metal will project into the tread or wear surface of the sole formed of the ridges or shoulders 16. It is ordinarily only necessary to drive staples into the portion of the sole formed by the several ridges 16 which will be beneath the ball of the wearer's foot, as indicated in Figures 1 and 2.

In order to permit the sole to be attached to an upper designed for a sole which is curved gradually upwardly toward the toe, the sole 22 may be bent to break it between the ridges which will be beneath the ball of the foot, namely, the ridges indicated by the letter A in Figure 1.

The edges of the wood or tread element 10a

of sole 22 may be sanded to the rounded form shown in Figure 1.

When closely grained, hard wood, such as birch, maple, poplar, or cherry is used, any breaking of the joints between the ridges 16 will be along irregular lines, as indicated at 18' in Figure 4. When the soles of the present invention are placed in actual use, the joints between ridges will break at other points according to the walking requirements of the wearer, but these breaks will also be along irregular lines. As a result, when the sole is in use, it will be impossible for any ridge to move vertically or translationally or to tilt laterally with respect to the next adjacent ridge. More particularly, if one ridge bears upon a protuberance in the ground or upon a small stone, it cannot move upwardly because, in effect, it will be interlocked at 18' with the next adjacent ridges by the small abutting shoulders formed in the opposite walls of the break 18'. This resistance to translational movement and lateral tilting of any ridge will be assisted because the entire material of the wooden tread surface is held closely together in a direction lengthwise of the sole by the nature of the fabric backing element 20a. Nevertheless, the irregular lines of breaking will not prevent one ridge portion of a sole from tilting upwardly on the "break" line with respect to an adjacent ridge portion. Also, when bending of the sole on a transverse line occurs during walking, the sole will be free to bend sharply upwardly at any point and the ridge portions adjacent the sharp bend may bend gradually. A sole will naturally be bent to this shape when the weight of the foot is placed upon the toe, that is, a sharp bend in the sole occurs immediately behind the toe and the portion of the sole immediately to the rear has a gradual bend imparted thereto.

As clearly shown in Figures 1 and 2, the toe 14a of a sole 22 is flat and ungrooved on its lower or tread surface, due to the fact that it is formed from the ungrooved portion 14 of a strip 10. Hence, the toe of the sole cannot bend upon itself. I have found that if the toe of a sole is permitted to bend upon itself, walking is somewhat more difficult, since when the weight of the foot is exerted through the toes, the downward pressure is exerted at two spots, one at the outer ends of the toes, and the other at the bases of the toes. The toe of a leather shoe sole will not bend upwardly between these points while the toe of the shoe is bearing all weight. The present sole gives the same desirable and non-bending support at the toe portion by the use of the non-bendable section 14a. Portion 14a is of sufficient length to extend to a point adjacent the base of the toes of the wearer, i. e., to a point adjacent the joints between the toes and ball of the foot.

It will be observed from Figures 1 and 2 that the rear edge of the toe portion 14a will present an upwardly and rearwardly beveled surface 25 when the sole is in use, because of the corresponding shape of the parent strips 10 best illustrated in Figure 6. This surface 25 assures adequate traction in soft ground at the time that the wearer's weight is being shifted from his rearward foot to his forward foot. Sufficient traction will be obtained at all other times by the rounded ridges 16, due to the fact that at any time when traction is exerted by these ridges, at least several of them will be bearing upon the surface being walked upon.

By separating the bases 17 of the rounded ridges 16 by the spacing portion 18, full use is obtained of the tractive or cleat effects of the sides 16a of the ridges or shoulders 16. In addition, because the spacing portions 18 space the rearwardly facing sides 16a of the ridges, better traction will be had in soft or rough ground since a larger area of such ground will be accommodated between the ridges and hence will be subject to pressure. Likewise, dirt will not be retained in the larger space thus provided between the ridges. Nevertheless, the spacing portions 18 insure that every portion of the backing element 20a will have a portion of the wood element 10a in contact therewith. That is, if the ridges 15 were simply spaced along the fabric element 20a by a distance corresponding to the width of the spacing portions 18, the intervening fabric could buckle and would be directly exposed to dirt and moisture. Furthermore, any ridge 15 could move upwardly and translationally or tilt laterally with respect to immediately adjacent ridges.

The provision of rounded ridges 16 is desirable because they eliminate sharp corners which might readily catch upon projections.

Throughout the greater portion of the foregoing, only the use of wood to form the tread element 10a has been discussed. However, it will be obvious that other bodily rigid, i. e., non-bending, materials, preferably having the same irregular breaking characteristics, could be used.

If it is desired to use a sole of the present invention with a rubber heel, the heel portion of the sole 22 can be entirely omitted and the remainder then used with a rubber heel or any other desired heel structure. In such cases, sufficient of the sole 22 would remain to provide the instep of the final shoe or sandal or, alternatively, even the instep portion of the present sole can be omitted so that the completed shoe or sandal would be fitted only with a toe and ball portion constructed in accordance with this invention. Where only the toe and ball are formed in accordance with this invention, only one strip 10 need be used to form the toe and ball.

It will be observed from Figure 3 that the opposed or side surfaces of adjacent ridges 16 recede from each other. That is, when the tread surface of the sole is facing downwardly, the opposed surfaces of the adjacent ridges will re-

cede from each other from their top portions, i. e., their portions adjacent backing element 20a, to their bottom portions. Because of this, each ridge is free to bend downwardly with respect to the next adjacent ridge. Hence, if longitudinal pressure is exerted upon a sole when its tread surface is facing downwardly, the sole will arch slightly upwardly so that the side or opposed surfaces of each adjacent ridge come into contact with each other, forming a rigid arch. This characteristic may be used to form a rigid instep, particularly when a shoe is to be provided with a raised heel. More particularly, if the sole is placed upon a shoe in such manner that the instep portion of the sole is subjected to longitudinal pressure, the instep portion will arch to form a rigid instep. In this way, a novel form of wooden-soled shoe, including an arched instep, may be formed from a normally flat sole of the present type, and without the necessity of initially shaping a solid wood blank to form an arch.

It will be appreciated from the foregoing that the present invention provides a sole which has qualities of flexibility and comfort very favorably comparable with those of a leather sole. Nevertheless, the sole need include no leather.

The terminology used in the specification is for the purpose of description and not of limitation, the scope of the invention being indicated by the claim.

I claim:

The method of making a shoe sole including a tread element formed of bodily rigid material comprising grooving a strip of the rigid material 35 of a width substantially equal to half the length of the sole to be formed, with the grooves extending longitudinally of the strip, the portion of the strip adjacent one edge thereof being left ungrooved, securing two of the strips in side by side 40 relation to a layer of bendable material with their grooves parallel and their ungrooved portions outermost, and cutting the soles from the strip material and bendable material along such lines that the length of each sole will extend transversely to the grooves and so that alternate soles 45 will extend in opposite directions and each will have its toe portion formed of the ungrooved surface of an alternate strip.

WARREN OAKLEY CAGNEY.
